J. J. Hatcher.

Pen & Pencil Case.

N° 11,314.

Patented Jul. 11, 1854.

Fig. 3.

Fig. 4.

UNITED STATES PATENT OFFICE.

JACOB J. HATCHER, OF PHILADELPHIA, PENNSYLVANIA.

PEN AND PENCIL CASE.

Specification of Letters Patent No. 11,314, dated July 11, 1854.

To all whom it may concern:

Be it known that I, JACOB J. HATCHER, of the city of Philadelphia and State of Pennsylvania, have invented a new and Improved 5 Pencil and Pen Case; and I do hereby declare that the following is a full and exact description.

The nature of my invention consists in the permanent attachment of the pencil to the 10 case in such a manner that the pen holder containing the reserve for leads is permitted to work over and entirely independent of the pencil. The pen holder in connection with the case by being slid backward and 15 forward uncovers and covers the everpoint pencil.

To enable others skilled in the art to make and use my invention I will proceed to describe its construction and operation.

20 Figure 1 represents the pen holder and reserve for leads. Fig. 2 represents the everpoint pencil. Fig. 3 represents a vertical section taken through the red line $\alpha\alpha$ of Fig. 4. Fig. 4 represents the case with the 25 tube C, slid into tube D, exposing the everpoint ready for use.

Similar letters in the several figures denote the same parts.

The tubes C, D, E, in Fig. 3 composing 30 the case may be made of any suitable metal and of such size as may be most convenient for carrying in the pocket and for writing. To the end of the tube C is attached a spring M, fitting in tube D, which gives it a regular 35 motion and which by coming against the projection in the end of tube D, prevents its being pulled apart. Also on the end of tube D is a similar spring N, working in tube E, but of greater strength, so that 40 when the tube D, is slid into the tube E, the tube C, with the pen holder F, can be slid in and out of the tube D, uncovering and covering the everpoint. Also when length as shown in Fig. 4, is desired, by sliding 45 tubes C and D out of tube E, tube C can be slid back into tube D without the tube D sliding into tube E. On the upper end of

the everpoint Fig. 2, B, is a collar or ring permanently attached to tube A, on the inside, and on the outside to the spring N, as 50 shown in Fig. 3. The reserve for leads is formed by the tubes J and K, the lever end of tube J being burnished or bent over so as to meet tube K, to which it is soldered, which forms the bottom of reserve. On the 55 upper end of tube J is a screw S, as shown in Fig. 1, in which the male screw P, which being hollow is made so as when screwed together the tube K filling the hole in screw P forms the upper end of the reserve to the 60 end of which is attached the pen holder F as shown in Figs. 1 and 3.

The operation of my pencil and pen case is as follows: By sliding the tube C into tube D it is ready for use. Should length of case 65 be desired the tubes C and D must be slid out of the tube E and the tube C slid back into the tube D, as seen in Fig. 4. The pen holder is operated by sliding out the tube J, or reserve, on the surface of which is a 70 ridge or projection O, as shown in Fig. 1, which prevents its being slid too far into the tube C, and reversing and sliding it back in the tube C when it is ready for use. Should length be desired the tube D must 75 be slid out of tube E.

Having thus fully described my improved pencil and pen case I do not claim the operation of a double extension case, nor do I 80 claim the combination of pen and pencil in one case. But

What I do claim as new and desire to secure by Letters Patent is—

1. The permanent attachment of the pencil A to the case D operating by the tube C 85 sliding over the pencil as set forth.

2. I also claim the hollow reserve for leads, with the pen holder working over and around the everpoint substantially in the manner set forth.

JACOB J. HATCHER.
